E. B. NATHAN

RECEPTACLE

Filed Nov. 23, 1922

INVENTOR
EDWIN B. NATHAN

BY
Morris Fishbein
ATTORNEY

UNITED STATES PATENT OFFICE.

EDWIN B. NATHAN, OF YONKERS, NEW YORK.

RECEPTACLE.

Application filed November 23, 1922. Serial No. 602,677.

This invention relates to receptacles or containers. More particularly, it is directed to a portable receptacle adapted to serve as a hat bag for ladies' hats or like articles.

One object of the invention is to provide a portable receptacle of the character described which shall be durable in construction, comparatively cheap to manufacture, 10 and simple and neat in appearance.

Another object of the invention is to provide a hat bag, the body of which is made from flexible material such as canvas or cloth and having reinforcing means adapted to maintain the shape of the bag, which 15 means may be detachable so as to permit the bag to be packed so as to occupy smaller space in shipping.

Other objects of this invention will in 20 part be obvious and in part hereinafter pointed out.

The invention accordingly consists in the features of construction, combinations of elements and arrangement of parts which 25 will be exemplified in the construction hereinafter described and of which the scope of application will be indicated in the following claim.

In the accompanying drawings, in which 30 is shown one of various possible illustrative embodiments of this invention,

Fig. 1 is a perspective view of a hat bag embodying this invention shown with the flap open so as to disclose the interior of 35 the bag;

Fig. 2 is an end cross-sectional view of the bag shown in Fig. 1;

Fig. 3 is an end elevation of the bag with the flap partially open; and

Fig. 4 is a vertical cross-section thereof 40 cut along line 4—4 of Fig. 3.

Referring in detail to the drawing, the hat bag embodying this invention there shown is seen to comprise a flat cylindrical body consisting of two circular base members 10, 11 and an annular wall member 12. The base members and the wall members are preferably cut to shape in separate panels and are then joined together in any suitable 45 manner. Thus in the form shown in the drawing, the edge of the base member 10 is inturned as at 10^a and the contiguous edge 12^a of the wall member 12 similarly inturned and then the base 10 and wall secured to each 50 other along the inturned edges by means such

as the line of stitches 13. If desired, a stiffening cord 14 may be employed to reinforce the bag at the point of junction between the base and wall. The latter may comprise a core 15 enclosed in a covering 16 made of 60 the same material as that of the bag. The edges of this covering 16 preferably extend inwardly and are joined to the inturned edges 10^a and 12^a by the same line of stitches 13. Similarly, the base 11 is secured to the 65 opposite edge of the wall member which is inturned in as at 12^b and stitched to the corresponding inturned edge 11^a of the base member by means of the stitches 17. A stiffening cord 18 may be employed at the point 70 of junction between the base 11 and the wall member and secured in the same member as already described with reference to the cord 15. Besides reinforcing the bag as explained, these stiffening cords 15 and 18 further serve to add ornamental appearance 75 thereto.

The wall member 12 is cut away for a portion of the circumference thereof at the front of the bag so as to provide an opening 19 large enough to admit a hat or like article such as indicated at 20. In providing this opening the material of the wall is preferably cut away from a point adjacent one of the bases such as 11 to the mid-height of 80 the wall, thus leaving a depending semi-wall portion 21. Secured to the base adjacent the ends of said opening 19 is a flap member 22 adapted to close said opening and of a width substantially equal to the height of the wall 85 member, so that when the flap is closed, it overlaps said portion 21 of the wall. For closing the flap, snap fasteners 23 are provided along the lower edge of the flap and along the sides thereof, these snap fasteners 90 consisting in male members 24 secured to one of the elements to be fastened together as for example, the member 21, and corresponding female members or sockets 25 secured to the other element, the flap 22.

The material from which the bag is made is preferably cloth, fabric, canvas or the like flexible material, and if desired, such cloth may be rubberized so as to make the bag waterproof. Means is provided for reinforcing the body of the bag so that it may maintain its shape as shown in Figs. 2 and 3. To this end, a separate reinforcing member 26 is provided comprising a substantially 95 rectangular band made of stiff yet pliable 100 material.

material, which is positioned on the inside of the bag and curved so as to rest against the rear portion of the wall member extending between the ends of the opening 19. This member 26 is preferably detachably secured to the walls of the bag as by means of snap fasteners 27, the co-operating parts 27^a, 27^b of which are secured respectively adjacent the ends of the reinforcing band and of the opening 19 respectively. Thus, when the bags are shipped in quantity, the bands 26 are packed flat thus permitting the bags to be flattened with their bases superimposed. In this way considerable economy of space is effected, as will be readily understood. At the front of the bag where the same is open to receive the article, it is not desirable to provide a continuous stiff reinforcing member since the flap 22 should remain flexible for facilitating the manipulation thereof. For this reason I provide the re-enforcement at the front of the bag by means of spaced rib members 28 made of strips of metal 29 or like stiff material secured in place in any suitable manner as by means of strips of material 30 covering said strips and stitched to the interior of the wall. For facilitating the carrying of the bag, a handle member 31 is provided which may be opened or closed 30 by means of a snap fastener 32.

It will thus be seen that there is provided a device in which the several objects of this invention are achieved and which is

well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

A receptacle of the character described comprising a pair of base members, a wall upstanding between said base members, said wall having a portion thereof cut away to provide an opening for the receptacle, said members and wall being formed of flexible, thin, sheet material to permit collapsing the receptacle when not in use, a continuous relatively stiff shape-retaining structure fitted to extend along the interior side of the uncut portion of said wall for retaining said base members and wall in an effective expanded position, a closure flap permanently attached to one of said base members, spaced ribs secured to said flap serving as a shape-retaining reinforcement therefor, and means adjacent said ribs for detachably securing the flap to the wall and the other of said base members.

In testimony whereof I affix my signature.
EDWIN B. NATHAN.
